PAPER MAKER'S DRIER FELT

Thomas Hindle and Sam Lord, Blackburn,
EnglandApplication August 2, 1938, Serial No. 222,682
In Great Britain August 23, 1937

2 Claims. (Cl. 139—408)

The invention relates to an improved construction of woven drier felt, as used on the drying cylinders of paper making machines, whereby the drier felt will give more efficient and better drying of the paper, that is to say, less steam will be required and the paper will be dried more evenly across the width of the sheet.

The function of a drier-felt on a paper machine is to press the moist web of paper uniformly and successively against the steam-heated cylinders of the machine, thereby facilitating the transmission of heat from the cylinders to the paper for the purpose of drying the latter.

Drier felts of known construction have a close homogeneous compact texture, and whilst moisture is readily absorbed from the paper, the passage of air through the felt from one face to the other is very restricted. As a consequence, a drier-felt of such known construction becomes saturated, in which condition, as the moisture fills up the small pores of the felt, it is even more impervious than when dry. Under these conditions the drying of the paper is seriously retarded, and it is essential to maintain the cylinders at a higher temperature than would be otherwise necessary, thus entailing a considerably higher steam consumption.

Furthermore, moisture-laden air may be trapped forming "pockets" between the paper and the felts, which "pockets" frequently prevent the paper being dried evenly across the width of the sheet.

To improve the drying of the paper, the drying sections of some paper machines are equipped with various systems of ventilation. In some of these systems heated dry air is forced into the spaces, or some of them, between the paper, felts, cylinders, etc., and in others the moisture-laden air is extracted from those spaces. In either case, the maximum useful effect of such ventilation is not obtained owing to the highly impervious nature of the drier felts of known construction.

The object of the invention is to provide a drier felt of greatly increased porosity, so as to permit air to pass very freely through the felt from one face to the other, according to the particular requirements of the ventilation system in use, but it will be understood that the improved drier-felt is also particularly advantageous if no special means for ventilation are available, inasmuch that natural ventilation is encouraged due to the pronounced porosity of the drier-felt.

Since the air passes freely through the felt

it is prevented from becoming saturated and the drying of the paper is thereby accelerated so permitting the cylinders to be operated at a lower temperature with a resultant decrease in steam consumption. Moreover, owing to the lower temperature to which the felt is subjected its useful life will be prolonged.

According to the invention the drier felt is woven with two or more layers having the warp and weft threads on face and back arranged in groups, each group comprising at least three threads, such groups being interwoven so as to form well-defined holes at the points where they intersect and so that these holes shall coincide in both or all layers of the drier-felt the weft threads of each group in one layer are in vertical alignment with those of the corresponding group or groups in the other layer or layers and the threads of the warp groups which interweave therewith are similarly in vertical alignment.

In the case of a two-layer drier-felt, the two layers may be bound together by an additional intermediate layer of weft, which layer may consist of the same number of weft threads as used to form the face and back layers, or alternatively may consist of a smaller number.

The invention will be described with reference to the accompanying drawing in which—

Fig. 1 is a view showing the appearance of the face and of the back of a felt woven in accordance with the invention.

Fig. 2 is a diagrammatic longitudinal section across the weft of a two-layer drier felt in which the surface weft threads and the warp threads are divided into groups of three and one binder weft is employed for a group of three wefts on each surface.

Fig. 3 is a diagrammatic transverse section across the warp of the two layer drier felt shown in Fig. 2.

Fig. 4 is a diagrammatic longitudinal section across the weft of a two-layer drier felt in which the surface weft threads and the warp threads are divided into groups of three, and two binder wefts are employed for a group of three wefts on each surface.

Fig. 5 is a diagrammatic transverse section across the warp of the two layer drier felt shown in Fig. 4.

Fig. 6 is a diagrammatic longitudinal section across the weft of a two-layer drier felt in which the surface weft threads and the warp threads are divided into groups of three and three binder wefts are employed for a group of three wefts on each surface.

Fig. 7 is a diagrammatic transverse section through the warp of the two layer drier felt shown in Fig 4.

In the weave illustrated in Figs. 2 and 3 for each repeat there are twelve individual warp threads *a*, i. e., four groups each of three threads and fourteen weft threads *b*, i. e., four groups each of three threads and two binder threads, one for each pair of groups of surface threads. The 10 warp threads are designated 1^a , 2^a — 12^a , and the weft threads 1^b , 2^b — 14^b , the threads 4 and 11^b being the binder threads.

As will be seen from Figs. 2 and 3, the first group of weft threads 1^b , 3^b and 6^b and the third 15 group 8^b , 10^b and 13^b form one surface of the felt and the second group 2^b , 5^b and 7^b and fourth group 9^b , 12^b and 14^b , the other surface, the first and third groups interweaving with the first group 1^a , 3^a and 5^a and the third group 7^a , 9^a 20 and 11^a of the warp threads and the second and fourth group with the second group 2^a , 4^a , and 6^a and fourth group 8^a , 10^a and 12^a of the warp threads. The binder weft 4^b being woven alternately with the first and fourth groups of warp 25 threads and the binder weft 11^b with the second and third groups thereof. Neither of the binder wefts 4^b and 11^b appear on the surfaces of the felt but lie between each pair of groups of the three surface threads.

30 The weave illustrated in Figs. 4 and 5 is similar to that shown in Figs. 2 and 3 except that four binder weft threads 3^b , 5^b , 11^b and 13^b are employed, the threads 3^b and 5^b following one path and the threads 11^b and 13^b the alternate path. 35 As before the twelve warp threads are divided into four groups 1^a , 3^a and 5^a ; 2^a , 4^a and 6^a ; 7^a , 9^a and 11^a ; and 8^a , 10^a and 12^a whilst the twelve weft threads forming the surfaces of the felt are divided into four groups 1^b , 4^b and 7^b ; 2^b , 6^b and 8^b ; 9^b , 12^b and 15^b ; and 10^b , 14^b and 16^b respectively. None of the binder wefts 3^b , 5^b , 11^b or 13^b appear on the surfaces of the felt but lie between each pair of groups of the three surface threads.

45 The weave illustrated in Figs. 6 and 7 is similar to that shown in Figs. 2 and 3 and Figs. 4 and 5 except that six binder weft threads 2^b , 5^b , 8^b , 11^b , 14^b and 17^b are employed, the threads 2^b , 5^b and 8^b following one path and the threads 11^b , 14^b and 17^b the alternate path. As before the twelve 50 warp threads are divided into four groups 1^a , 3^a and 5^a ; 2^a , 4^a and 6^a ; 7^a , 9^a and 11^a ; and 8^a , 10^a and 12^a whilst the twelve weft threads forming the surfaces of the felt are divided into four 55 groups 1^b , 4^b and 7^b ; 3^b , 6^b and 9^b ; 10^b , 13^b and 18^b ; and 12^b , 15^b and 18^b respectively. None of the binder wefts 2^b , 5^b , 8^b , 11^b , 14^b and 17^b appear on the surface of the felt but lie between each pair of groups of the three surface threads.

60 Instead of the weft threads and warp threads being divided into groups of three they may be divided into groups of four or more in which case the number of binder weft threads for each pair of groups may be any number from one up to the number of threads in a group.

65 A felt woven as hereinbefore described pro-

duces a pronounced hole *x* at each of the points where the groups of warp *a* and weft *b* intersect and the formation of these holes may be assisted by reeding the warp with six warp threads per dent, i. e., the warp threads forming each pair of groups. If each group contains four warp threads then they could be reeded eight threads per dent and so on. This however is not essential, as the interweaving of the weft causes the grouping of the warp threads and the interweaving of the 10 warp causes the group of the weft threads on the face and back.

In a felt woven according to the invention there is no tendency for the groupings of the warp and weft threads to be lost and consequently 15 when the drier felt is running on the paper machine the holes *x* will not be removed.

The improved drier-felt may be woven from vegetable, animal, mineral or artificial threads, or any combination thereof, according to partic- 20 ular requirements.

What we claim as our invention and desire to protect by Letters Patent is:

1. A two layer drier felt comprising groups of 25 weft threads and groups of warp threads on the face and back, the threads of each group lying continuously in side by side relationship and each group containing the same number of threads and at least three, the groups of weft threads of the face being interwoven with the 30 groups of warp threads of the face and the groups of weft threads of the back being interwoven with the groups of warp threads of the back and the groups of each layer being in vertical alignment with those of the other layer whereby well 35 defined coinciding vertical holes are formed at the points where the groups of weft threads intersect the groups of the warp threads and a plurality of intermediate binding weft threads not greater in number than the threads in each 40 surface group, for binding the two layers together which binding weft threads do not appear on either surface but lie between the surface groups each binding thread lying in the same perpendicular plane as a pair of weft threads in the top and bottom surfaces respectively so that it will not obscure any of the vertical holes.

2. A two layer drier felt comprising groups of 45 weft threads and groups of warp threads on the face and on the back, the threads of each group lying continuously in side by side relationship and each group containing three threads, the threads both weft and warp of one group of one surface being in vertical alignment with the 50 corresponding group of the other surface whereby on interweaving the weft and warp groups of each surface well defined vertical holes are formed, the holes in each surface being in alignment and binder weft threads of a number not 55 greater than three which do not appear on either surface but lie between them the threads of each group lying continuously in side by side relation- 60 ship.
